UNITED STATES PATENT OFFICE.

THOMAS EUGENE SIKES, OF DODGE COUNTY, AND SIMEON R. SIKES, OF HELENA, GEORGIA.

BALING-PRESS.

SPECIFICATION forming part of Letters Patent No. 653,757, dated July 17, 1900.

Application filed October 24, 1899. Serial No. 734,672. (No model.)

To all whom it may concern:

Be it known that we, THOMAS EUGENE SIKES, residing in Dodge county, and SIMEON R. SIKES, residing at Helena, in the county of Tel-fair, State of Georgia, citizens of the United States, have invented certain new and useful Improvements in Baling-Presses; and we do declare the following to be a full, clear, and exact description of the invention, such as 5 will enable others skilled in the art to which it appertains to make and use the same, reference being had to the accompanying drawings, and to the letters of reference marked thereon, which form a part of this specification.

15 Our invention relates to improvements in baling-presses; and it consists in a peculiar arrangement and organization of instrumentalities for baling hay, straw, &c., by means of which the power applied to the plunger 20 for compressing the material to be baled increases in proportion as said material becomes compressed. After full compression by a quick return action the plunger is wholly withdrawn from the baling-box, and 25 for an appreciable time it remains substantially at rest, giving sufficient time to fill the baling-box in front of the plunger with material to be compressed before the plunger is again moved forward, the principal object of 30 our invention being the means employed for quickly withdrawing the plunger from the baling-box immediately on the completion of its inward stroke.

Referring to the drawings, Figure 1 is a 35 plan view of our improved baling-press. Fig. 2 is a side elevation of the same viewed in the direction of the arrow 2, Fig. 1. Figs. 3, 4, and 5 are plan views of the plunger-operating mechanism in different positions.

40 The baling-box A is constructed in the usual well-known form, having a solid top and bottom and open sides through which the baling-wire is passed for tying the bales. An opening or mouth is made in the top of the 45 baling-box at its rear end, through which material to be packed is fed. The baling-box is long enough to contain two bales, which are separated from each other by a grooved partition-board a, the forward bale serving as an 50 abutment against which the new bale is compressed. The area of the outlet end of the

baling-box is slightly less in cross-section than the body of the box, by which means a resistance is offered to the outlet of the completed bale, the latter thus serving as an 55 abutment against which the new bale is formed. As the formed bale travels through the baling-box fastening-wires are passed through the grooves in the partition-board a and around the bale. Bolts a', passing 60 through timbers a² at the outlet end of the baling-box, serve to regulate the size of the outlet end and the resistance offered to the exit of the bale, the result being a more or less tightly packed bale. 65

The baling-box A, which lies in a horizontal position upon the ground, is secured to two longitudinal beams B, one on each side of the box, at the bottom. These beams B, which are secured by bolts b to two other 70 beams C, extend a considerable distance rearwardly of the baling-box in a longitudinal direction and are bolted to a footpiece D. A separating-block E, placed between the beams C at their outer ends and secured thereto 75 and to the footpiece D, carries a vertical journal or stud d, on which is centrally pivoted a straight lever F, carrying a roller f at each end. A sweep G, bolted to the lever F, is provided with suitable couplings for the attachment of horses. The plunger H within the baling-box is attached to the forward end of a plunger-rod H', its rear end being preferably shod with a metal plate h and having a bar h' attached to one side and reaching beyond the plate h. Near the extreme rear end of the power-stand, formed by the beams C, footpiece D, and separating-block E, is pivoted at one end a vibrating lever I, to which, at its free end, is in turn pivoted a link or coupling 80 bar J, the other end of which is journaled to the plunger-rod at j between the plunger H and the metal plate h. The inner side of the vibrating lever I carries a V-shaped projection or tooth I', so placed as to be struck by the rollers f on the straight lever F as it is rotated by the sweep G. A short distance forward of the separating-block E is a cross-timber C', bolted to the beams C, which forms a rest or slide to carry the weight of the rear end of 85 the plunger-rod H'. A curved guide or rail K, attached at one end to the timber C', curves 90 95 100

outwardly and forwardly on one side of the power-stand and then turns inwardly as far as the beam C, to which it is bolted. A pin h^2 , which may carry a roller, depends from the under side of the plunger-arm H' and bears against the inner side of the guide or rail K as the plunger is driven into the baling-box. Springs a^3 , attached to the inner sides of the baling-box, act in the usual manner to prevent the return of material when the plunger is withdrawn. Across the mouth of the baling-box, at its forward side, is a yielding bar A', which extends into the throat of said box below the under surface of its top side. It is attached to flat springs a^5 , as shown, and yields upwardly on the advance of the plunger to permit the material to enter the baling-box. It also serves in the same manner as springs a^3 to prevent the material from returning.

Hay, straw, or other suitable material to be bundled having been placed in the baling-box A through its mouth, power is applied to the sweep. The plunger, being in its rearmost position, is now advanced by the roller f engaging the shod end h of the plunger-rod H' as the sweep G, with the lever F, is rotated on the vertical stud or journal d. (See Fig. 4.) In this position the power applied to the plunger is least effective, because the plunger-rod H' and lever F are at a right angle to each other. At the same time the material in the baling-box is soft and easily compressed. As the sweep continues to move around in the direction of the arrow the angle between the plunger-box and lever becomes greater and greater, thus increasing the power expended in compressing the material, which now becomes more compact. Gradually approaching a straight line, the plunger-bar and lever are in position to exert their greatest power against the mass of material, which now offers the greatest resistance. (See Fig. 5.) During this action the pin h^2 on the plunger-bar H' has been guided inwardly by the rail K, keeping the plunger-bar and lever always in connection. The plunger-bar H' and lever F having reached a straight line, the roller f bearing on the end of the plunger-bar rolls off, and the other roller f on the opposite end of the lever F, striking the V-shaped projection I', (see Fig. 1,) quickly pushes the vibrating lever I rearwardly (see Fig. 3) and withdraws the plunger by means of the connecting-rod J from the baling-box. After passing the V-shaped projection I' the roller f strikes the bar h'

and pushes the plunger-rod laterally without advancing the plunger, at which time new material is placed in the baling-box. Each semirotation of the sweep G moves the plunger into and out of the baling-box.

Referring to Figs. 1 and 3, it will be seen that a comparatively-small movement of the sweep is required to withdraw the plunger from the baling-box. After the plunger has been withdrawn it rests while the sweep makes about one-eighth rotation, the plunger-rod being moved laterally during this movement. Finally the forward movement of the plunger takes place, which requires a quarter-rotation or more of the sweep for its full stroke.

Having thus described our invention, we claim—

1. In a baling-press, the combination with the baling-box, its plunger and plunger-rod, the plunger-rod being mounted so as to move laterally and having a projection extending beyond and parallel with its end, of a vibrating lever connected with the plunger-rod, and a centrally-pivoted rotatable lever located in relation to said lever and plunger-rod that in its rotation its ends will successively engage a part of the vibrating lever to retract the plunger-rod, then engage the projection of the plunger-rod to move the rod laterally, and then engage the end of the rod to move it longitudinally, substantially as described.

2. In a baling-press, the combination with the baling-box, its plunger and plunger-rod, the plunger-rod being mounted so as to move laterally and having a projection extending beyond and parallel with its end, of a vibrating lever having a projection, a link or rod connected at one end to said lever and at its opposite end to the plunger-rod, and a centrally-pivoted rotatable lever located in relation to said lever and the plunger-rod that in its rotation its ends will successively engage the projection of the vibrating lever to move said lever outwardly and retract the plunger-rod, then engage the projection of the plunger-rod to move the rod laterally, and then engage the end of the plunger-rod to move it longitudinally, substantially as described.

In testimony whereof we affix our signatures in presence of two witnesses.
